UNITED STATES PATENT OFFICE.

JOHN W. PAGE, OF CHICAGO, ILLINOIS.

EXCAVATING DEVICE.

Application filed November 24, 1922. Serial No. 602,968.

To all whom it may concern:

Be it known that I, JOHN W. PAGE, a citizen of the United States, residing at Chicago, in the county of Cook and State of Illinois, have invented a new and useful Improvement in Excavating Devices, of which the following is a specification.

This invention relates to certain new and useful improvements in excavating devices, 10 and is fully described and explained in the specification and shown in the accompanying drawings, in which Figure 1 is a view in side elevation, showing the bucket on the trolley, Fig. 2 is a similar view showing the 15 bucket in the position it occupies just after the sheave 18 has engaged the stop block 19, Fig. 3 is a similar view showing the bucket dumped, Fig. 4 is a view in front elevation of the sheave over which the holding chain 20 operates, and Figs. 5 and 6 are views in side 25 elevation of the same sheave showing the holding chain in different positions thereon.

The excavating device herein shown is of 25 the same general type as, and an improvement on, the excavating device shown in my Patent No. 1,194,777, dated August 15, 1916, and its general method of operation is substantially the same. The particular features 30 of difference between this device and the one shown in said patent will be particularly pointed out herein.

Referring to the drawings, 5 indicates a cableway provided with the usual means whereby it may be tightened and slackened. 35 This cableway is similar to the one shown in my prior patent referred to above. The present device has been found particularly useful in excavating gravel pits and for similar purposes where it is sought to dump 40 the material from many successive bucket loads in a predetermined position, as in a hopper (not shown) arranged under the bucket, when it is in the position shown in Fig. 3. The general arrangement of the 45 trolley with respect to the gravel pit, and the location of the hopper, are all shown in my prior patent, above referred to, and consequently need not be shown here, since the 50 operation of the device in respect to these features is substantially the same as in said prior patent. The bucket takes its load in the usual way and may be raised by tightening the cable 5. After being loaded the bucket is pulled forward by any suitable 55 means to the position where it is to be dumped. The inclination of the cableway

5 is such that the bucket will run down to the point at which it is sought to have it work, and therefore there is required no mechanism for hauling it in a backward direction in this particular instance. Mounted upon the cableway 5 is a trolley which may be of any desirable form, here shown as a triangular frame 7 carrying rollers or wheels 8 running upon the cableway. Attached to the under side of the trolley is a bail 9, to which is swivelled an excavating shovel 10, the point of the pivot preferably being behind the center of gravity of said shovel. The bail 9 may be of any suitable form and is here shown as formed of two chains separated near their lower ends by means of the spreader bar 9'.

11 indicates the hauling chains, 12 is the holding chain thereof, and 13 is the loading line or main hauling line, to which the holding chain 12 and the two hauling chains 11 are attached, as is common practice in the Page buckets now used for excavating purposes.

In the device here shown, the holding chain 12 runs over a block 15 attached to the trolley 7. The novelty in the present case lies in the particular construction and operation of this block 15 and the holding chain 12. These parts, and operation thereof, will now be described more in particular. The block 15 is attached to the under side of the trolley 7. Over this block runs the holding chain 12, the forward end of which is secured to the main hauling line or loading line 13. From this point it runs upwardly and backwardly over the block 15 and thence is led downwardly to the upper forward part of the bucket, where it is attached at the center as indicated by 14. The block 15 is provided with a double-grooved sheave 15', shown removed from the block in Fig. 4. The two grooves of this sheave are concentrically arranged, one being larger than the other. I have indicated the smaller groove by 76 and the larger groove by 77. The larger groove is formed by the flanged disks 78 forming the sides of the sheave. The holding chain 12 carries at one point a lock bar 81. This bar is preferably made of stiff metal bent slightly at the center and having a diameter small enough so that it will pass between the disks 78 and run down on the smaller groove 76 (see Fig. 5). The rest of the holding chain 12 is large enough so that it will not pass between the disks 78,

but will run up on the larger groove 77 at the periphery of the disks 78 (see Fig. 4). The locking bar 81 is so placed in the chain 12 that when the bucket is in its normal position, before it has commenced to dump (as shown in Fig. 1), said bar will be in a position substantially as shown in Fig. 5. When in this position, it will be noted that the locking bar 81 is in between the disks 78 resting on the smaller groove 76. This will give a leverage in favor of the end of the holding chain 12 attached to the end of the loading line or main hauling line 13, so that but a slight tautness on said hauling line 13 will serve to maintain sufficient tension on the holding chain 12 to prevent dumping of the shovel. As soon as the tautness of the hauling line 13 is released, even though slightly, permitting the shovel to tilt, the locking bar 81 is moved to a position below the sheave 15', as shown in Fig. 6, thus causing the holding chain 12 to run up on the larger groove 77 of the sheave, and thus destroying the leverage referred to above.

25 The operation of the device is as follows. 16 is a sheave carried preferably at the point where the holding chain 12 joins the loading line 13. A rope 17 connected to the trolley 7 runs under the sheave 16 and up to another 30 sheave 18, which runs on the cableway 5. 19 is a stop-block on the cableway at the point where the dumping is to occur. As 35 the bucket is drawn forward, the sheave 18 strikes this block 19 and is pushed back toward the trolley, thus shortening the bight in the rope 17 and drawing the trolley 7 forward. The bucket in this position, after engagement with the sheave 18 with the block 19, is shown in Fig. 2. The result is that 40 both of the hauling chains 11 and the holding chain 12 are slightly slackened, thus permitting the front of the bucket to descend. As soon as this occurs, the locking bar 81 moves out of the sheave 15' to the position 45 shown in Fig. 6. As soon as this occurs, the leverage existing in favor of holding the bucket in its horizontal position, is destroyed, as explained above. When in this position the bucket may be dumped by slackening away slightly on the hauling line 13 thus giving a little slack to the holding chain 12 to permit full and complete dumping of the bucket. The bucket in complete dumping position is shown in Figure 3. It 50 is to be particularly noted that the position of the locking bar 81 on the smaller groove 76, as shown in Figure 5, assists in preventing the dumping of the bucket. When the locking bar is in this position, only a very 55 slight tension on the hauling rope line 13 will prevent dumping. When the sheave 18 engages the block 19 the trolley 7 is pulled forward. This permits the bucket to tilt far enough to release the locking bar, whereupon 60 the bucket may be readily dumped by a

slight slackening of the hauling line. Only enough engagement between the sheave 18 and the block 19 is required in order to advance the trolley 7 forward enough to give enough slack in the holding chain 12 to permit the locking bar 81 to come out of the sheave 15', as shown in Figure 6.

In the foregoing specification, I have shown how the engagement of the sheave 18 with the stop 19 serves to pull the trolley 7 forward to release the locking bar. It is to be noted, however, that the bucket may be dumped without the use of any such stop or sheave. For example, the rope 17, sheave 18, and stop 19 can all be omitted and the bucket can be dumped by slackening away on the main hauling line 13 sufficiently to cause enough slackening of the chain 12 to permit the locking bar 81 to move out of the sheave 15'. Obviously, however, if the sheave 18 and stop 19 and their associated parts are dispensed with, considerably more slackening of the hauling line 13 is required at the start to release the locking bar.

90 While I have shown and described certain embodiments of my invention, it is to be understood that it is capable of many modifications. Changes, therefore, in the construction and arrangement may be made 95 without departing from the spirit and scope of the invention as disclosed in the appended claims, in which it is my intention to claim all novelty inherent in my invention as broadly as possible in view of the prior art. 100 What I claim as new and desire to secure by Letters Patent, is:

1. In an apparatus of the character set forth, the combination of a main cable, a carriage movable thereon, a scraper bucket pivotally mounted on said carriage in the rear of the center of gravity of the bucket when loaded, a hauling line for pulling the bucket along said main cable, a block attached to the carriage, a holding chain running from the front of the bucket over said block to the hauling line, means arranged in connection with said block whereby a leverage in favor of the end of the holding chain attached to the hauling line is established when the bucket is in load-retaining position and destroyed when said bucket is in partial or complete dumping position, and means engaging said hauling line in advance of said bucket operating at 110 a predetermined point to accelerate the movement of said carriage along said main cable relative to the movement of said hauling line, for the purpose set forth.

2. A block provided with a sheave having two concentrically arranged grooves of different sizes, in combination with a chain adapted to run over the larger groove thereof and provided with a locking bar adapted to run down on the smaller groove thereof. 130

bucket is in partial or complete dumping position, a block running on said main cable, a stop on said cable on the path of movement of said block, and a cable connected with said block and carriage and operatively engaging said hauling line for the purpose set forth.

11. In an apparatus of the character set forth, the combination of a main cable, a carriage movable thereon, a scraper bucket pivotally mounted on said carriage in the rear of the center of gravity of the bucket when loaded, a hauling line for pulling the bucket along said main cable, a block attached to the carriage, a holding chain running from the front of the bucket over said block to the hauling line, said block so constructed that a leverage in favor of the end of the holding chain attached to the hauling line is established when the bucket is in load-retaining position and destroyed when said bucket is in partial or complete dumping position, a block running on said main cable, a stop on said cable on the path of movement of said block, and a cable connected with said block and carriage and operatively engaging said hauling line for the purpose set forth.

12. In a device of the class described, the combination with a suitable shovel, of supporting means pivoted thereto behind the center of gravity thereof, hauling means pivotally secured to the front of the shovel, a block attached to the supporting means, a holding-chain running from the front of

the shovel directly over said block to the hauling means, and means arranged in connection with said block for establishing a leverage in favor of the end of the holding chain attached to the hauling means when the shovel is in a horizontal position and for destroying said leverage as the shovel commences to tip.

13. In a device of the class described, the combination with a suitable shovel, of supporting means pivoted thereto behind the center of gravity thereof, hauling means pivotally secured to the front of the shovel, a block attached to the supporting means, and a holding chain running from the front of the shovel over said block to the hauling means, said block so constructed as to establish a leverage in favor of the end of the holding chain attached to the hauling means when the shovel is in a horizontal position and destroy said leverage as the shovel commences to tip.

14. A block provided with a sheave having two concentrically arranged grooves of different sizes, in combination with a chain running over said sheave, a portion of said chain being adapted to run over the larger groove of the sheave, and a member connecting said first referred to portion of chain with a second portion thereof, said connecting member being adapted to run on the smaller groove of said sheave.

Witness my hand and seal, this 20th day of November, 1922.

JOHN W. PAGE. [L. s.]
